UNITED STATES PATENT OFFICE.

NATHANIEL M. BAIN, OF OAK GROVE, OREGON.

SEGREGATING-NEST.

1,395,078.

Specification of Letters Patent. Patented Oct. 25, 1921.

Application filed November 9, 1920. Serial No. 422,948.

To all whom it may concern:

Be it known that I, NATHANIEL M. BAIN, a citizen of the United States, and a resident of Oak Grove, county of Clackamas, 5 State of Oregon, have invented a new and useful Improvement in Segregating-Nests, of which the following is a specification.

This invention relates generally to devices used by the poultrymen for segregating 10 those members of his flock of hens which do not lay eggs.

My invention has for its object the providing of a trapnest so constructed that a hen entering the nest will be trapped therein, unless she lays an egg. My invention besides specifically has for its object the providing of a simple and efficient device embodying the following salient features.

A hen entering the housing of my device will, upon sitting in the nest therein provided, operate certain mechanism which will automatically close a door at the entrance of the housing thus confining the hen. If the hen leaves the nest 25 without having laid an egg, the door will remain shut, and the hen can only be released manually; and thus the poultryman may segregate the hen from his flock. But if the hen has laid an egg, the latter will roll onto a door-releasing mechanism adapted to be 30 actuated by the weight of the egg and operate to open the door automatically and thus permit the hen to leave.

Then I provide besides, marking mechanism operated by contact of the body of the hen with a part of such mechanism, whereby there will automatically be placed on the hen's body a drop of pigment to mark her as she emerges from my segregating nest; 40 and in that way identifying this hen as a layer.

The above specified and incidental features of my invention are hereinafter more fully described, and are fully shown in the 45 accompanying drawing, in which:

Figure 1 shows a perspective view of my device, with the near wall removed, so as to show the general construction of parts, all parts are shown in their normal inactive positions;

Fig. 2 shows a longitudinal section of my device showing a hen sitting on the nest, all parts of the device being shown in that position in which they are placed 55 by the action of the hen in entering and sitting on the nest;

Fig. 3 shows a detailed view of the door, and of the marking mechanism with the parts in their normal, inactive position;

Fig. 4 shows a view similar to Fig. 3, but 60 with the door raised, and the marking devices operated by the assumed action of the hen as she walks out of my segregating nest; the operation being caused by the contact of her body with a member of the marking 65 mechanism;

Fig. 5 is a perspective detail, showing the construction of the removable top or cover 70 of the housing of my device;

Fig. 6 is a fragmentary detail illustration 70 in the action of the tiltable floor through which the door-releasing means is operated; and

Fig. 7 is a perspective detail of the same 75 means.

My device comprises a pair of the side walls *a* of the housing, only the distant one of which walls is shown in Fig. 1, and a removable top or cover *b*. The walls are joined together by the transverse end wall *a'* and piece *a''*. The floor *c* is tiltably mounted on a rod *d* supported between the side walls *a*. A door *e* is pivotally supported from the ends of pairs of parallel arms *f* and *g*, one set of which is located adjacent 85 each side wall, and said arms are pivoted on pins *h* and *i* respectively supported by the side walls *a*. The short ends *f'* of the arms *f* are connected to the inner end of the floor *c* by means of cords *j*. Thus when the door 90 *e* is in a closed position, the arms *f* will have been rocked clockwise, and the inner end of the floor *c* will have been raised.

The nest consists of a boxlike structure *k* open at one end and pivotally mounted 95 on the rod *m* which is supported between the walls *a*. The side *k'* of the nest *k* extends beyond the rod *m* and upon this is mounted an adjustable weight *n* for holding the nest in the raised position when the same 100 is empty, (see Fig. 1). A lever *o*, pivotally mounted on a pin *p*, sets in line with one side of the nest *k*. A finger *q* fixed to the edge of nest *k* is adapted to bear against the lever *o*, when the nest *k* is tilted to the position 105 shown in Fig. 2, thus causing the lever *o* to rock in a counter clockwise direction. The upper end of the lever *o* is connected by means of a cord *r* to a latch *s*, which is pivoted to one side wall at *s'*, as shown in Fig. 110 4. This latch hangs normally in a vertical position and when the door *e* is raised, the

latch will engage the bottom of the door so as to hold the same open (see Fig. 4). When the lever o is rocked counter clockwise the latch s is drawn back so as to release the door e , which will then fall to a closed position as it is of greater weight than the floor c (see Fig. 2).

To hold the floor c in the raised position when the hen has stepped upon the same 10 from the fulcrumed nest, I provide a latch t , hinged to the under side of the floor, and which has a notch t' adapted to engage with a projecting lip u' of the piece u carried by the bar w rigidly mounted on a shaft v which 15 is rotatably mounted between the side walls of the housing. The floor is thus held as shown in Fig. 2, with the latch t acting as a strut.

On one end of the bar w is mounted a 20 tray x for receiving the egg when the nest k resumes its normal or inclined position, because of the hen jumping from the nest back onto the floor c . At the other end of the bar w is an adjustable counter weight y , which 25 normally holds the bar w in the position in which it is shown in the full lines of Fig. 2. When an egg rolls on the tray x its weight rocks the bar w counter-clockwise to the position shown by the dotted lines of Fig. 2, 30 throwing the latch t at such angle that its notch no longer will engage with the lip u of the bar w . To insure that the depression of the bar w will throw the latch t out of engagement the former has mounted on it a 35 finger 17 which functions to push the latch off the lip u .

While passing out of the housing the hen has automatically placed upon her a drop of pigment so that she may be recognized as 40 a layer.

For the latter purpose I provide mechanism comprising a lever-arm 2 pivotally mounted upon a bracket 3 rigidly supported by the outer face of the door e . The inner 45 end of the arm 2 carries a pivoted pendant rod or dauber 4 ; on the other end of the arm 2 is an adjustable weight 5 tending to hold the arm as shown in Fig. 3.

A container holding pigment 6 (see Fig. 50 4) is placed in an opening in the floor c , directly beneath the dauber 4 , and a hinged cover 6^a , normally closes the open top of the container 6 . An arm 6^b connecting the cover 6^a with the lower end of the lever o , operates 55 to remove the cover when the lever o is rocked counter-clockwise, and to replace it when the lever o is rocked in the opposite direction, (see Fig. 1). The lever o and rod 6^b are located at one side of the floor c so as 60 to clear the latter.

A cord 7 is secured to the outer end of the lever arm 2 and the other end of the cord is tied to the frame member a^2 . When the door e is in the raised position, the cord 7 65 is slack as shown in Fig. 4, but when the

door is lowered, the cord is taut and pulls the outer end of the lever-arm 2 up, and thus causes the dauber 4 to dip into the pigment in the container 6 . When the door e is again raised, a drop of pigment will be 70 carried by the lower end of the dauber 4 ready to be deposited upon the back of the hen as she leaves the housing.

The dauber 4 carries a weight 20 tending to hold it against a cleat 21 fixed on the 75 bottom of the door e , and the dauber 4 works in a staple or guide 22 .

It is not desirable to have the dauber 4 drag pigment over the body of the hen, but only to deposit on her a drop of the pigment. To insure this effect I provide means for instantly lifting the dauber 4 upon having touched the hen, such means being arranged as follows:

A flap 9 is pivotally pendent from the 80 bracket 10 which is carried by the door e . A catch 11 provided on the upper end of the flap 9 is adapted to engage with an arm 12 , which is pivotally hung from the arm 2 . On the lower end of the arm 12 , is pivoted a 90 latch-bar 18 one end of which engages with the catch 11 of the flap 9 ; and from the other end of which is pivotally hung a trigger-bar 19 .

Thus when the hen passes through the 95 door-way her body will come in contact with the flap 9 and she will swing that outward into its position as shown in Fig. 4. In so doing she will cause the catch 11 of the flap 9 to engage with the latch-bar 18 100 which resists tilting by reason of the weight of the trigger-bar 19 suspended therefrom as mentioned, and hence the pressure of the catch 11 on the latch-bar 18 will result in pulling the arm 12 downward and tilting the 105 arm 2 to the position in which it is shown in Fig. 4, thereby causing the dauber 4 to touch the back of the hen and deposit its drop of pigment. When the hen feels the 110 touch of the dauber on her back she will involuntarily rise, and in so doing push upward the trigger-bar 19 thereby tilting the latch-bar 18 to such degree as to cause the catch of the flap 9 to slip from it, thereby releasing the arm 12 and hence permitting the weight 5 to function to tilt the arm 115 2 so as to lift the dauber 4 .

Should it happen that the hen does not rise when feeling the touch of the dauber 4 , and thus does not operate the trigger-bar 120 19 she would finally move the flap 9 outward to such extent as to cause the arm 13 of the catch 11 to bear against and move the arm 12 to such degree as to break the engagement of the catch 11 with the latch-bar 18 .

A vertical wall 14 , padded with any soft material, prevents the egg from rolling off the open end of the tray x . A lever 15 pivotally mounted on the member 14 and con- 130

nected to the nest-arm *k'* by a link 16, serves as a stop for the tray *x*, when the latter drops to the position shown in dotted lines in Fig. 2. When the nest is again lowered 5 by another hen, the lever 15 will be rocked to the position shown in the full lines in Fig. 2, thus permitting the arm *w* carrying said tray *x* to drop still further and let the egg roll off on the floor or into a box. The 10 tray *w* is then lifted to its normal position by the counter-weight *y*.

I will now describe the cycle of operation of my device: Normally when not in use, the parts of my device will be positioned 15 as shown in Fig. 1. It is to be noted that the door *e* is open, and a hen may freely enter through the entrance of the housing. The hen so entering, will pass under the door *e*, and hop onto the nest *k*. Her weight 20 will then cause the nest to tilt downward into a horizontal position, whereupon the door-closing devices will operate to release the door *e* and permit it to close, and all parts will assume the positions shown in 25 the full lines of Fig. 2. The hen is now trapped within the nest. When she is ready to leave the nest *k*, she will hop onto the floor *c*. If she has not laid an egg, there will be no consequent operation of the parts, 30 and she will remain trapped, and can be released only by manually operating my device. If however, she has laid an egg, the latter will roll onto the tray *x* of the bar *w*, depressing the latter so as to disengage 35 the latch *t*, and when the hen then jumps back onto the floor *c* her weight will cause the latter to tilt down to a horizontal position. The described mechanical connections 40 between this floor and the door *e*, will then cause the latter to open, and thus permit the hen to walk out. However, as the hen passes through the entrance of the housing, her back will brush against the flap 9, and thus bringing into action the dauber 4 will 45 deposit a drop of marking liquid on the back of the hen.

I claim:

1. In a segregating nest, a housing, marking means, located in the housing, a pigment carrying impinging dauber and operating means therefor, including a one-way actuating member arranged to be operated by the hen brushing there against on walking out of said housing.
2. In a segregating nest, a housing, a door at the entrance of the housing, marking means, carried by the door, means for charging the marking mechanism with pigment, and an operative connection of such means with the door, whereby the mechanism is charged with pigment simultaneously with the closing of the door.
3. In a segregating nest, a housing, a door at the entrance of the housing, marking

means, carried by the door, such marking means also including a pendant dauber, a pigment holder, and means operating to insert the dauber in said holder in unison with the closing of the door.

4. In a segregating nest, a housing, a de- 65 pressible nest, a door at the entrance of the housing, means connecting the door with the nest, whereby the door is opened and shut relatively to the movement of the nest, marking means, carried by the door, means 70 for charging the marking mechanism with pigment, and an operative connection of such means with the door, whereby the mechanism is charged with pigment simultaneously with the closing of the door.

5. In a segregating nest, a housing, a de- 75 pressible nest, a door at the entrance of the housing, means connecting the door with the nest, whereby the door is opened and shut relatively to the movement of the nest, marking means, carried by the door, such 80 marking means also including a pendant dauber, a pigment holder, and means operating to insert the dauber in said holder in unison with the closing of the door.

6. In a segregating nest, a housing, a tilt- 85 able floor at the entrance of the housing, a door at the entrance of the housing, door operating means connected with the tilttable floor and the door, arranged to tilt the former when the latter is shut, and to open the door when the floor is placed in normal position, a nest hinged at one end, being normally inclined, and adapted for being depressed, said door operating means being 90 operated to close the door by the depression of the nest, a latch for locking the floor in inclined position, such latch being placed in its active state when the floor is inclined by the closing of the door, means for releasing the latch, such means including a tray to receive the egg rolling from the nest when resuming its normal inclined position, said means being operated by the weight of the 95 egg.

7. In a segregating nest, a housing, a tilttable floor at the entrance of the housing, a door vertically movable at the entrance of the housing, a connection thereof with the tilttable floor whereby the door is operated 100 relatively to said floor and is opened when the floor is in its normal position, a de- pressible nest, means, operated by the depression of the nest, to close the door, a means automatically locking the floor when 105 in its inclined position, and door releasing means including a tray into which the egg laid in the nest is deposited, said means being operated by the weight of the egg.

8. In a segregating nest, a housing a tilt- 110 able floor at the entrance of the housing, a door vertically movable at the entrance of the housing, a connection thereof with the

- tiltable floor whereby the door is operated relatively to said floor and is opened when the floor is in its normal position, a de-
5 pressible nest, means, operated by the de-
pression of the nest, to close the door, a means automatically locking the floor when in its inclined position, a fulcrumed arm carrying a tray at one end to receive the egg deposited in the nest when the latter is in-
10 clined, a latch carried by said arm, such latch coöperating in said floor locking means and the latch being released when the tray-carrying end of said arm is depressed.
9. In a segregating nest, a housing, a tilt-
15 able floor at the entrance of the housing, a door vertically movable at the entrance of the housing, a connection thereof with the tiltable floor whereby the door is operated relatively to said floor and is opened when
20 the floor is in its normal position, a de-
pressible nest, means, operated by the de-
pression of the nest, to close the door, a means automatically locking the floor when in its inclined position, a fulcrumed arm carry-
25 ing a tray at one end to receive the egg de-
posited in the nest when the latter is in-
clined, a weight normally so holding said arm as to place its said tray in its egg re-
ceiving position, said weight being adapted
30 to be over balanced by the egg laid in said tray, a latch carried by said arm, such latch coöperating with said floor locking means and the latch being released when the tray-carrying end of said arm is depressed.
- 35 10. In a segregating nest, a housing, a tiltable floor at the entrance of the housing, a door vertically movable at the entrance of the housing, a connection thereof with the tiltable floor whereby the door is operated
40 relatively to said floor and is opened when the floor is in its normal position, a tilt-
able nest, means, operated by the tilting of the nest, to close the door, a means automatically locking the floor when in its in-
45 clined position, and door releasing means

including a tray into which the egg laid in the nest is deposited, said means being operated by the weight of the egg.

11. In a segregating nest, a housing, a tilt-
50 able floor at the entrance of the housing, a door vertically movable at the entrance of the housing, a connection thereof with the tiltable floor whereby the door is operated relatively to said floor and is opened when the floor is in its normal position, a tiltable nest, means, operated by the tilting of the nest, to close the door, a dog hinged to and pendent from the floor, a fulcrumed arm carrying a tray at one end to receive the egg deposited in the nest when the lat-
55 ter is inclined, a latch carried by said arm, such latch coöperating with said dog and the latch being released when the tray-carrying end of said arm is depressed.

12. In a segregating nest, a housing, a door, marking-means located in the entrance of the housing, such means including a pendent dauber, a pigment holder, means connected with the door operating to insert the dauber in the pigment holder when the door is closed, means for holding the dauber in its active state, means for releasing the dauber and causing it to assume its inactive state, the latter means being actuated by the contact of the dauber with the hen's body.

13. In a segregating nest, a housing, a door, marking means located in the entrance of the housing, such means including a pendent, counter-weighted dauber, a pigment holder, means connected with the door operating to insert the dauber in the pigment holder when the door is closed, means for holding the dauber in its active state, means for releasing the dauber and causing it to assume its inactive state, the latter means being actuated by the contact of the dauber with the hen's body.

NATHANIEL M. BAIN.
